TRAYLIKE FOLDING STRUCTURE

Marshall I. Williamson, New Haven, Conn.

Application November 9, 1946, Serial No. 708,950

6 Claims. (Cl. 229—32)

1

This invention relates to folding structures formed of foldable sheet material, such as paper board ordinarily employed in the manufacture of folding paper boxes.

The folding structure of the invention is particularly useful in its application to the construction of collapsible folding boxes and other devices for the retention and/or display of merchandise, and the invention is concerned not only with the folding structure per se, but also with the boxes, displays, and other devices for whose formation the structure is employed.

The existing high-speed automatic equipment employed in the manufacture of folding paper boxes limits the contour or configuration of such boxes almost entirely to the prosaic rectangular shapes commonly produced. It is therefore, highly desirable in that industry, from the standpoint of competition with other types of boxes to which, because of rapidly advancing technological development, this limitation does not equally apply, to devise folding boxes, displays, etc., of more decorative or ornamental configuration, which still can be produced on the said existing high-speed automatic machine.

Such improved folding boxes and displays must, naturally, be not only ornamental, but structurally strong and adequately protective of their merchandise content as well. In addition, where they are to be produced in large quantities, as is usually the case, they must be capable of quick and easy manual or mechanical erection, filling, and closing by the manufacturer or packer of the ultimate contents.

An object of the present invention, therefore, is to provide folding structure which will make possible the quick and economical production of collapsible folding boxes and other devices of ornamental configuration possessing considerable strength and resistance to rough handling.

A further object is to provide folding structure, as above, which will render folding boxes and other devices in which it is employed capable of being easily and quickly set-up into usable form from collapsed shipping and storage condition.

Folding structure produced in accordance with the invention is characterized by articulated panel sections, which are outfolded into angular relationship relative to one another, forming wall facets, and it is the peculiar interrelation of certain groups of these wall panel sections which constitutes the generic concept inherent in all embodiments of the invention.

A very important feature of the invention resides in the articulating of one group of wall

5 panel sections, foldable into wall structure presenting a plurality of facets, angularly to at least one other group of substantially similarly formed and arranged panel wall sections, so that, when properly outfolded, they combine to reinforce each other and to provide basic wall structure, there being other wall panels associated therewith to complete the wall formation.

10 A usual and preferred form of the folding structure involves 30°, 60°, and 90° angular relationships between component parts thereof, but other forms may involve different angular relationships without departing from the generic concepts of the invention.

These and other objects and features of the invention will be apparent from the following detailed description of the preferred specific embodiments illustrated in the accompanying drawings, in which:

15 Fig. 1 is a perspective view of a set-up display container pursuant to the invention;

Fig. 2 is a section taken on the line 2—2, Fig. 1;

Fig. 3 is a longitudinal section taken on the line 3—3, Fig. 1;

20 Fig. 4 is a view corresponding to that of Fig. 1 drawn to a slightly reduced scale and illustrating certain of the wall panels opened out to reveal reinforcing and supporting wall panels therebelow; and

25 Fig. 5 is an outside face view of the flat blank, which is cut and scored to be folded and glued into collapsed tubular form and thereupon set-up into the display container of the preceding figures.

Referring to the drawings: the illustrated embodiment is a display container in the form of an ornamental tray adapted to contain and display merchandise.

30 As illustrated, the tray possesses a flat bottom 10 bordered by upstanding walls of outfolded formation presenting a plurality of ornamental facets. The upstanding walls comprise side walls 11, 11 and end walls 12, 12.

In use, merchandise rests upon the bottom 10 of the tray and is retained by the side and end walls 11, 11 and 12, 12, respectively. A transparent wrapper, not shown, may be applied to the tray as a protection for the contents, without concealing desirable ornamental features of the container nor interfering with display of such contents.

35 In accordance with customary practice in the folding box industry, the tray is formed by properly folding, gluing, and setting-up a suitably cut and scored blank of foldable sheet material po-

sessing the requisite shape-retaining characteristics, the material ordinarily employed being paper-box board.

A blank pursuant to the present invention, cut and scored for the formation of the finished tray of Fig. 1, is illustrated in Fig. 5. It comprises bottom wall panels 10a and 10b, sets of side wall panel sections 11a, 11b and 11a, 11b arranged for outfolding, sets of end wall panel sections 12a, 12b and 12a, 12b arranged for outfolding, and sets of end wall supporting panel sections 12c, 12d, 12e, 12f and 12c, 12d, 12e, 12f likewise arranged for outfolding. In addition, there are opposite tuck-in tabs 13, 13 and a glue lap 14.

The various wall panels, wall panel sections, and other parts of the blank of Fig. 5 are defined by scores or creases, indicated in the drawings by light broken lines, and by cuts, indicated by unbroken lines. Only those scores and cuts of special significance will be singled out for discussion, it being understood that folding occurs on the scores, and separation, ordinarily, on the cuts.

In the instant case, the bottom wall panels 10a and 10b are the only panel portions of the blank complete in themselves, that is to say, the only ones not classified as "panel sections" and intended to be individual, angularly related components of a single wall structure, as are a set of panel sections 11a, 11b, which together form a side wall 11 of the finished tray, or a set 12a, 12b, which together form an end wall 12 of the finished tray.

In the construction of the finished tray, the blank is first folded into what is known as "collapsed" form, and glued to provide a tubular, foldable body. This can be and preferably is carried out on well known automatic machinery widely used in the folding box industry. The folding may occur on either the longitudinal score lines 15 and 16 or the longitudinal score lines 17 and 18, and glue or equivalent adhesive is preferably applied to the glue lap 14, as indicated, so that such glue lap is affixed to the inside marginal surface of bottom wall panel 10a, see Fig. 2. It should be noted that, to permit such folding of the complete blank on the longitudinal score line 17 or the longitudinal score line 16, such score lines are longitudinally extended through the end panel sections 12c, 12c and 12e, 12e, respectively, as indicated at 17a, 17a and 16a, 16a, respectively.

As thus folded and glued into the said "collapsed" form, setting-up is accomplished by sliding the inner bottom wall panel 10b laterally until it is substantially centrally placed over outer bottom wall panel 10a, see Fig. 2, the side wall panel sections 11a, 11b and 11a, 11b assuming the outfolded triangular formation of side walls 11, 11, and the thereto angularly related end wall panel sections 12c, 12d, 12e, 12f and 12c, 12d, 12e, 12f thereby automatically assuming the partially telescoped outfolded triangular formation of end wall supporting structure 20, 20, Fig. 4. Completion of the setting-up operation is accomplished by folding the end wall panel sections 12a, 12b and 12a, 12b over their respective supporting structure 20, 20 and tucking tabs 13, 13 through the respective slots 21, 21, Fig. 3, at the inner bases of said supporting structure.

In the illustrated embodiment, the angles marked by arcuate arrows, Fig. 5, are 60°. This must be so if the finished tray is to be of the preferred rectangular formation having walls of substantially equilateral triangular formation in cross-section. Also, it is desirable that the cut

lines 22, 22 and 23, 23 be slightly arcuate, as shown, so as to provide sufficient openness for the slots 21, 21 to conveniently receive the respective tuck-in tabs 13, 13. Too, it has been found desirable to perforate the longitudinal score lines 24, 24, defining the inner bottom wall panel 10b, to facilitate the setting up and collapse of the tray.

It should be noted that there is here presented a novel teaching of how to construct a triangular tubular wall which is in itself integral, yet bent or folded upon itself at right angles without body distortion.

Whereas this invention has been illustrated and described with respect to certain preferred specific embodiments thereof, it should be understood that various changes may be made in said embodiments and various other embodiments may be constructed by those skilled in the art without departing from the spirit and generic purview of the invention as defined by the following claims.

I claim:

1. A folding tray container formed of shape-retaining flexible sheet material, comprising two oppositely disposed wall panels, one larger than the other and the two adapted to lie together in face-to-face contacting relationship when the container is set up; oppositely disposed outfolded sets of integrally and articulatively related wall panel sections joining said wall panels together along corresponding opposite sides thereof and making up, respectively, together with portions of the larger one of said wall panels, oppositely disposed faceted wall structure of substantially equilateral triangular formation in cross-section when the said container is set-up; oppositely disposed outfolded sets of integrally and articulatively related wall panel sections making up, respectively, oppositely disposed supporting structure likewise of substantially equilateral triangular formation in cross-section when the said container is set-up; said supporting structure being integrally and articulatively connected directly to said wall structure and adapted to stand at substantially right-angles thereto when the said container is set-up; oppositely disposed sets of integrally and articulatively related wall panel sections connected to one of said wall panels along opposite free sides thereof and adapted to fold over the said outfolded supporting structure, respectively, and to lie thereagainst when the said container is set up; and tuck-in tabs secured to the last-named sets of wall panel sections, respectively, for securing the said container in substantially rigid, strongly reinforced set-up tray formation.

2. A rectangular folding tray-like receptacle formed from a cut and scored blank of shape-retaining foldable sheet material which has been folded upon itself and joined to provide a collapsed, open-ended, tubular shell, said receptacle, when formed from said blank, comprising a double-thick bottom made up of an outer bottom panel and of a substantially similar but smaller inner bottom panel superimposed upon the said outer bottom panel in face-to-face relationship therewith; opposite hollow triangular side walls made up of respective pairs of elongate inner and outer panel sections which are longitudinally joined together and longitudinally joined to the said outer bottom panel and the said inner bottom panel, respectively; and opposite hollow triangular end walls made up of respective hollow triangular supporting and reinforcing structure

and respective inner and outer panel sections extending integrally from a bottom panel folded thereover and secured in place, said hollow triangular supporting and reinforcing structure of each of said end walls comprising sets of integrally joined inner and outer panel sections which extend integrally, respectively, from the ends of said inner and outer elongate panel sections of the said opposite side walls so that each of said sets presents a completely integral corner-forming extension of its corresponding side wall.

3. A wall structure formed of foldable sheet material, and comprising, a bottom portion; a first wall portion hingedly connected to the bottom portion along a bottom fold line; a second wall portion hingedly connected to the first wall portion along a ridge fold line, the three portions forming a hollow wall of triangular cross section; and an end structure integral with said wall structure and foldable from a first position coplanar with said wall portions into a second position at an angle with respect to said first position, said end structure comprising a plurality of panels hingedly interconnected along fold lines 25 intersecting said ridge fold line at a point of intersection, the two endmost of said panels being hingedly connected to said first and said second wall portions, respectively, along fold lines also running to said point of intersection.

4. A wall structure formed of foldable sheet material, and comprising, a bottom portion; a first wall portion hingedly connected to the bottom portion along a bottom fold line; a second wall portion hingedly connected to the first wall portion along a ridge fold line, the three portions forming a hollow wall of triangular cross section; and an end structure integral with said wall structure and foldable from a first position coplanar with said wall portions into a second position at an angle with respect to said first position, said end structure comprising three panels hingedly interconnected along lateral fold lines meeting said ridge fold line at a common point, the two endmost of said panels being hingedly connected to said first and said second wall portions, respectively, along lateral fold lines also running to said common point.

5. A wall structure formed of foldable sheet material, and comprising, a bottom portion; a 50

first wall portion hingedly connected to the bottom portion along a bottom fold line; a second wall portion hingedly connected to the first wall portion along a ridge fold line, the three portions forming a wall of triangular cross section; and an end structure integral with said wall structure and foldable from a first position coplanar with said wall portions into a second position at an angle with respect to said first position, said end structure comprising a plurality of panels hingedly interconnected along lateral fold lines, the two endmost of said panels being hingedly connected to said first and said second wall portions, respectively, along lateral fold lines, the said lateral fold lines being aimed at a common point on said ridge line defined by the intersection of the ridge line with at least two of said lateral fold lines.

6. In a folding tray-like receptacle formed of shape-retaining foldable sheet material, the combination with a hollow side wall structure of triangular cross section comprising a bottom panel portion, an outer wall panel portion hingedly connected to the bottom panel portion along a bottom fold line, and an inner wall panel portion hingedly connected to the outer wall panel portion along a ridge fold line, of an end structure extending integrally and angularly from both the outer and inner wall panel portions of 30 said side wall structure along a pair of fold lines, said end structure comprising a plurality of panel portions integrally interconnected along fold lines intersecting said ridge fold line at a common point, and said pair of fold lines also intersecting the ridge fold line at said common point.
